UNITED STATES PATENT OFFICE.

GEORGE FRASER, OF SIOUX LOOKOUT, ONTARIO, CANADA.

AUTOMATIC OIL CUP.

Application filed October 11, 1922. Serial No. 593,788.

To all whom it may concern:

Be it known that I, GEORGE FRASER, of the village of Sioux Lookout, in the Province of Ontario, Canada, have invented certain new 5 and useful Improvements in Automatic Oil Cups, of which the following is the specification.

The invention relates to improvements in automatic oil cups and particularly to such 10 devices as are in use in connection with the air pumps of locomotives and the like and the principal object of the invention is the provision of a device which is automatic in operation and simple in construction, being 15 controlled by the reciprocations of the piston of the air pump to deliver oil into the cylinder thereof at intervals in comparatively small quantities, as drop by drop. The air pump controls the operation of the oil cup 20 by means of the variations in the air pressure caused by the reciprocations of the piston.

A further and more specific object is to 25 arrange the structure of the oil cup such that the same can be readily taken apart or assembled and such that the valve plunger can be easily removed if desired in order to permit of the substitution of a similar valve 30 plunger having a larger feed passage to accommodate a different kind of oil.

With the above more important objects in view the invention consists essentially in the arrangement and construction of parts hereinafter more particularly described and later 35 pointed out in the appended claims, reference being had to the accompanying drawing in which:

Fig. 1 is a side view of the automatic oil cup.

40 Fig. 2 is an enlarged detailed vertical sectional view centrally through the cup.

Fig. 3 is a side view of the valve plunger.

Fig. 4 is a horizontal sectional view at 44 Fig. 3.

45 In the drawing like characters of reference indicate corresponding parts in the several figures.

The body 1 of the device is in the form of 50 a hollow oil receiving casing or cylindrical receptacle having the upper end thereof open and exteriorly screw threaded as indicated at 2 and the lower end thereof reduced and formed with downward and upward extensions 3 and 4 providing a cylindrical plunger receiving tubular casing. The upper and lower ends of this latter casing are exte-

riorly screw threaded, the lower end receiving a flanged coupling 5 and the upper end receiving a cap screw 6. The extension 4, which, it will be observed, extends upwardly 60 within the bottom of the receptacle 1, is provided at the bottom of the receptacle with an inlet opening or port 7. The cap 6 is provided with a tubular extension 8 which passes well toward the top of the receptacle 65 and provides an air escape passage 9 connecting the upper end of the extension 4 with the top end of the receptacle 1. A screw cap or cover 10 is screw threaded onto the upper end of the receptacle 1 and the 70 cover is also provided with an air escape passage 11.

A feed pipe 12 is connected by the coupling 5 to the lower end of the extension 3 and this feed pipe passes to the cylinder of 75 the air pump of the locomotive and feeds the oil in the manner, as shortly described, to the cylinder.

The lower end of the extension 3 is supplied with an interior ledge or seat 13 which 80 is adapted to act as a stop to limit the lowermost position of the valve plunger 14 which is slidably mounted within the extensions 3 and 4. The valve plunger is prevented from rotating within the extensions 85 in any suitable manner, such as by the provision of a tongue 15 formed at the upper end thereof, the tongue being slidably received within a lengthwise extending slot or groove 16 provided in the extension 4, the 90 slot being of sufficient length to permit of the full end sliding movement of the plunger.

The plunger is fitted with an interior centrally disposed and longitudinally extending feed passage 17 which communicates with the side port 18, the port 18 being designed in the uppermost position of the plunger to register with the port 7.

The plunger is held normally seated on 100 the ledge 13 by the action of a coiled compression spring 19 interposed between the cap 6 and the upper end of the plunger and having the ends seated in suitable sockets counter sunk in such latter parts. 105

The lower end of the plunger carries a valve 20 adapted to open downwardly to permit the passage of the oil to the pipe 12 and to close upwardly under the action of the air pressure in the pipe 12. The valve 110 employed is provided with a flat sided shank or stem 21 which is slidably received within

a pocket 22 formed in the lower end of the plunger and the valve is prevented from escaping from the pocket by cutting an annular groove 23 in the stem and passing a pin 24 across the groove, the pin being carried by the plunger. Sufficient clearance is provided in the groove to permit of the opening and closing of the valve, it being understood that the valve seats against the 10 lower end of the plunger. The valve is shown open in Figure 2 of the drawing.

The body of the plunger is exteriorly cut away to provide an annular chamber 25 which in all positions of the plunger is in 15 communication with an air escape opening 26 formed in the side of the extension 3. This latter arrangement permits of the escape to atmosphere of any air under pressure which might leak past the lower end of 20 the plunger.

The operation of the device is as follows, it being understood that the receptacle 1 is filled with lubricating oil as indicated at 27 and that the pipe 12 is connected to the air 25 pump cylinder of the locomotive.

On the up stroke of the piston of the air pump the increase in the pressure of the air thereabove operates through the pipe 12 to initially force up and seat the valve 20 and 30 prevents any passage of air through the passage 17 of the plunger after the said valve has seated. The air pressure overcomes the resistance of the spring 19 and accordingly forces the plunger upwardly until the upper 35 end thereof engages with the cap 6, at which time the ports 7 and 18 are in registration. A small quantity of oil is accordingly permitted to flow from the receptacle 1 through the ports into the passage 17.

On the return or down stroke of the piston of the air pump a partial vacuum is created in the upper portion of the cylinder thereof and this decreases the pressure in the pipe 12 and permits the spring 19 to 45 force the plunger down and pass the ports

out of registration. It also frees the valve 20 to open so that the small quantity of oil in the feed passage will be passed down the tube 12 to the cylinder of the air pump before the piston starts its next upward stroke. 50

This delivery of a small quantity of oil to the cylinder during each cycle of operation of the piston effectively lubricates the cylinder.

As oil varies considerably one can readily 55 adapt the plunger to the kind of oil being used by either supplying a plunger with a larger or smaller feed passage, as the occasion requires, or by increasing or decreasing the size of the feed passage in the plunger 60 provided.

What I claim as my invention is:

In a device of the character described, the combination of a cup-shaped receptacle, a cover closing the upper end of the receptacle 65 and provided with an air escape passage placing the interior of the receptacle in communication with the atmosphere, the bottom of said receptacle being provided with a central opening and with tubular 70 wall portions projecting in opposite directions and in line with said opening, means for closing and connecting the lower tubular wall portion to the cylinder of an air pump, a cap closing the upper tubular wall 75 portion and equipped with a hollow extension extending vertically therefrom to terminate at a point above the level of the oil contained in the receptacle, and a pressure controlled valve mounted to slide in said tubular wall portions and to control the passage of oil from the receptacle to the cylinder of the air pump connected therewith. 80

Signed at Winnipeg, this 4 day of April 1922.

GEORGE FRASER.
